Patented July 18, 1961

190,943

COMBINED BILLFOLD AND CHANGE PURSE

Samuel J. Smallman, 373 5th Ave., New York, N.Y.

Filed Jan. 23, 1961, Ser. No. 63,656

Term of patent 14 years

(Cl. D87—3)

FIG. 1

FIG. 2

FIG. 3

Des. 190,943

PAGE 2

FIG. 4

FIG. 5

FIG. 1 is a front elevational view of a combined billfold and change purse showing my new design;

FIG. 2 is a rear elevational view;

FIG. 3 is an edge elevational view;

FIG. 4 is a perspective view with elements in open condition; and

FIG. 5 is a plan view of the inner portions thereof.

I claim:

The ornamental design for a combined billfold and change purse, substantially as shown.
